S. LOW & C. H. KIRBY.
GOLF CLUB HOLDER.
APPLICATION FILED JAN. 27, 1913.

1,092,729.

Patented Apr. 7, 1914.

UNITED STATES PATENT OFFICE.

STANLEY LOW AND CHARLES HARRY KIRBY, OF LONDON, ENGLAND.

GOLF-CLUB HOLDER.

1,092,729.

Specification of Letters Patent.

Patented Apr. 7, 1914.

Application filed January 27, 1913. Serial No. 744,490.

To all whom it may concern:

Be it known that we, STANLEY Low and CHARLES HARRY KIRBY, both subjects of the King of Great Britain, both residing in 5 London, England, and whose post-office address is Westminster House, Great Smith street, Westminster, in the county of London, England, have jointly invented certain new and useful Improvements in Golf-Club Holders, of which the following is a specification.

In carrying golf clubs in ordinary golf bags, the handles are apt to rub against one another and also may be injured by coming 15 in contact with the metal heads of other clubs, so that the handles, or binding or covering of the handles become rubbed, loose or cut, causing inconvenience to the player. In addition, in wet weather 20 the handles of the clubs are liable to rub against the wet club heads making them slippery and difficult to hold. It has been proposed to overcome these objections by constructing a bag longitudinally divided into a 25 number of fixed or removable long pockets each adapted to accommodate the shaft of a club, each pocket being held distended at its mouth by a metal or other ring, fastened in position by sewing or otherwise or 30 by other means.

The present invention relates to an improved golf club holder serving to keep the clubs separate and protect them from injury. The improved holder may be constructed with or without an inclosing case, and when made without a case, it can be 35 utilized as an auxiliary to an ordinary golf bag to effect the same purpose.

It also relates to a special arrangement 40 of the holder in the golf bag or inclosing case, so as to allow of this being divided into two or more compartments which can be utilized for carrying balls, golf boots, or other articles. The holder may be provided 45 with the usual shoulder strap for carrying purposes.

The invention will be described with reference to the accompanying drawings in which—

50 Figure 1 is a perspective view of a golf club holder constructed according to this invention and provided with an inclosing case; Fig. 2 is a vertical section of the holder in Fig. 1; Fig. 3 is a perspective view 55 of the top and bottom parts of a holder

showing one way in which the separate pockets or compartments may be arranged and held in position when the holder is utilized as an auxiliary to an ordinary golf bag; Fig. 4 is a perspective view of the top 60 part of an ordinary golf bag or an inclosing case with a portion of the auxiliary part shown in Fig. 3 attached; and Fig. 5 is a perspective view of the lower part of a holder showing a modified arrangement. 65

The holder comprises a number of separate pockets or compartments *a* which may be parallel as in Fig. 3 or inclined to the ends of the holder and converge toward one another in the downward direction as 70 depicted in Fig. 5; each golf club can thus be placed in a separate compartment and kept quite free from rubbing against the neighboring clubs. The holder may be provided with a partition wall *A'*, Fig. 5, so 75 that when used as an auxiliary to a golf bag or inclosing case, a chamber devoid of clubs is constituted within the bag. The separate compartments can be made of leather, canvas, seamless hose piping or any 80 suitable material and are affixed to a top plate *b* provided with suitable holes, the axes of which holes may, like the compartments in Fig. 5, converge toward one side of the holder. The compartments are 85 attached to a bottom plate *c* which may form the bottom of the holder. Each or one or more of the separate compartments *a* may be provided with means, such as spring 90 clips *d*, Fig. 3, by which it can be temporarily affixed to the bottom plate *c*. When the holder is used in conjunction with an inclosing side wall *A* of suitable material the top and bottom plates *b* and *c* may be 95 fixed to the wall *A* by stitching, riveting 100 or in any suitable manner, or detachably secured as by straps.

A hood or cover *h* may be permanently attached to the wall *A* as denoted in broken lines, Fig. 2, or made detachable and carried either in a pocket provided at the side of the wall, or within the inclosing wall itself, an opening *i* with flap door *j* and fastenings *k* being provided on the wall *A* to allow of this. A pocket *l* may be provided for carrying the balls, and a ring *m* and socket *n* for holding an umbrella or walking stick may be attached to the outside of the wall or case *A*. 105

The inclosing case or bag *A* may be di- 110

vided into two chambers by means of a partition A', Fig. 1, which may be of canvas or other suitable material. A bag so constructed, when the auxiliary is withdrawn or is 5 not used, has separate compartments one for accommodating the clubs, the other for golf boots or other articles. When the holder is to be used with a bag that already possesses a partition wall as just referred to, 10 a partition wall in the holder is unnecessary.

When the holder is used as an auxiliary for ordinary golf bags, the top and bottom plates *b* and *c* with the separate compartments *a* are made of such a size that they 15 can be inserted into the bag, which serves as an inclosing case. The bottom plate of the holder would rest on the end or bottom of the bag, the top plate of the holder being fastened to the bag by any suitable means, 20 such as by straps *e* in Fig. 3, which may be affixed to the end plate and engage in holes provided for the purpose on the bag. In Fig. 4, such straps engage in holes under the rim of the bag around which they are fastened.

The improved bag or auxiliary holder may be composed of a certain number of fixed compartments and a certain number of detachable compartments, or they may 30 be all fixed or detachable.

The upper parts of the separate compartments *a* are preferably fixed to the top plate *b* in such a way as to protect the edges of the fabric of which they are composed such 35 as by stitching their edges between the two leathers constituting the top plate as shown at *f*, (Fig. 3). In the case of the detachable compartments the upper parts are preferably affixed to rings held in position by 40 making the holes in the upper leather larger than the holes in the under leather of the top plate, thus forming a countersunk hole as shown at *g*, in which the rings engage, so that any or all the compartments can be 45 removed if desired.

Having thus described the nature of our said invention and the best means we know of carrying the same into practical effect, we claim:—

50 1. A golf bag comprising in combination an inclosing case having a body wall, a club holder consisting of a bottom plate, a top plate having a plurality of apertures, a plurality of open-ended flexible club-receptacles connecting the top and bottom plates, said receptacles arranged each with an end in register with an aperture in the top plate, and means for securing the holder in position within the inclosing case.

60 2. A golf bag comprising in combination, an open-mouthed inclosing case consisting of a body wall and a bottom wall, a club holding device consisting of a top plate having a plurality of apertures, a plurality of 65 open ended club receptacles of flexible ma-

terial connected with the top plate and arranged each with an end in register with an aperture in the top plate, means for securing the top plate to the body wall and means for detachably securing a receptacle end to the 70 bottom wall of the case.

3. A golf bag comprising in combination, an inclosing case consisting of a body wall and an end wall, a removable club holder consisting of a bottom plate adapted to bear 75 on said end wall, a top plate having a plurality of apertures, a plurality of open-ended tubular club-receptacles of flexible material connecting the top and bottom plates, said receptacles arranged each with 80 an end in register with an aperture in the top plate, and means for detachably securing the holder in position within the inclosing case.

4. A golf club bag comprising in combination, an apertured side wall constituting an inclosing case, a partition wall secured within the case to the said side wall and forming compartments in the case, one compartment communicating with one end of 90 the case and another communicating with an aperture in the side wall, a closing device for said aperture carried by the wall, a pocket member attached to the inner surface of said side wall and having a mouth 95 communicating with a second aperture therein and means carried by the said side wall adapted to close said second aperture, a club holder disposed within one of said compartments and comprising a top plate, a bottom plate, a plurality of open-mouthed club-receptacles having their lower ends attached to the bottom plate and their mouths 100 communicating each with an aperture in the top plate, the axes of the receptacles being arranged at an inclination to the said top plate and in a manner to converge toward one another in a downward direction and means for detachably connecting said holder to the inclosing case.

5. A golf club bag comprising in combination, an apertured side wall and an end plate constituting an open-mouthed inclosing case, a partition wall secured within the case to the said side wall and an end plate 115 forming compartments in the case, one compartment communicating with one end of the case and another communicating with an aperture in the side wall, a closing device for said aperture carried by the wall, a pocket member attached to said side wall and having a mouth communicating with a second aperture therein and means carried by the said side wall adapted to close said 120 second aperture, a removable club holder disposed within one of said compartments and comprising a top plate, a bottom plate, a plurality of open-mouthed club-receptacles having their lower ends attached to the bottom plate and their mouths 125 communicating 130

each with an aperture in the top plate, the axes of the receptacles being arranged at an inclination to the said top plate and in a manner to converge toward one another in a downward direction, and means for securing said holder to the inclosing case.

In testimony whereof we have signed our

names to this specification in the presence of two subscribing witnesses.
